UNITED STATES PATENT OFFICE.

JOHN W. PEARSON AND JOSEPH S. POWER, OF DAYTON, OHIO, ASSIGNEES TO THE DAVIS SEWING MACHINE COMPANY, OF DAYTON, OHIO, A CORPORATION OF DELAWARE.

VALVE.

Application filed March 28, 1921. Serial No. 456,163.

To all whom it may concern:

Be it known that we, JOHN W. PEARSON and JOSEPH S. POWER, citizens of the United States, residing at Dayton, in the county of 5 Montgomery and State of Ohio, have invented certain new and useful Improvements in Valves, of which the following is a specification, reference being had therein to the accompanying drawing.

10 Our invention relates to valves and in particular to valves on a drain.

We have shown our invention adapted to a drain on a washing machine, one of its preferred adaptations. The object of our 15 invention is to provide a valve which will readily seat itself, which may be operated from a distance from the valve, and which will not necessitate machining in order to provide a perfect seating of the valve.

20 In washing machines, which must be built cheaply and in large quantities, the elimination of any machine work where possible, is essential. It is also essential that the drain for the washing machine be located at a convenient point below the machine while the 25 operation of the drain should be at the top of the machine so that the operator will not have to bend over to get the water out of the tub. One of the great objections to the modern power washing machine is the difficulty

30 of draining it. In many washing machines it is customary to have an internal hump or division in the bottom of the tub over which the water and clothes are drawn. This adds 35 additional difficulties to draining the tub as there must be two outlets from the tub proper communicating with, preferably, a single exit.

It is also the object of our invention to 40 provide a drain which will not necessitate a projecting spout to convey away the waste water as this spout would interfere with the operation of the mechanism to which the drain is attached and in which the valve is 45 installed.

Referring to the drawings:

Fig. 1, is a diagrammatic view of a washing machine tub, drain and valve installed in combination.

50 Fig. 2, is a section of the valve and the bottom of the tub to which it is attached with the control wire broken in order to include the entire operating mechanism within the scope of the drawing.

55 Referring to the drawing, 1 is the bottom

of a washing machine tub, 2 is that portion of the tub which rises abruptly as a hump in the bottom of the tub, 3 is the bottom proper of the tub in which there is a grating 4 to prevent the clothes from falling into the opening and area occupied by the valve itself. 5 is a drain casing which communicates at one end with a drain pipe 6. This drain pipe 6 is not essential but in some types of washing machines is installed so that it 60 will communicate with the other side of the tub on the other side of the hump 2 and thereby permit of draining of both sides of the tub.

7 is an opening in this drain casing 5 through which the water enters the drain casing from the tub 1. In normal operation the area 8 within the casing 5, as well as the area within the tube 6, is filled with water and one of the problems to be solved 70 is to so construct the operating means for the valve that a special packing will not be necessary. This is accomplished in the present instance by the use of a Bowden wire control consisting of a casing 9 and an operating wire 10. This wire and casing are conveyed upwardly to the top of the tub where a suitable support 11 will maintain it in position. An operating head 12 is mounted on the end of the wire. As the 75 point of exit of the wire 10 is above the general level of the water, no special packing is necessary.

The casing 9 is rigidly secured in the tube 6 at 13 and projects downwardly and laterally, terminating in a head 14. This head 14 serves as a guide for the plug 15 which slides upon it. The plug 15 is actuated by the wire 10 which is fastened to it between the nuts 16 and 17. This member 15 is a 80 pear-shaped body having a metallic casing on its head at 18. A rubber gasket 19 is placed in the orifice 20 of the casing 5. The pear-shaped member 15 and its casing 18 engage with this rubber gasket 19 thus 85 making a tight fit. The Bowden wire control holds the member 15 in close engagement with 19. This eliminates all necessity for machine work. A simple casting 15 is sufficient; the rubber 19 makes a close connection and a water tight arrangement to prevent the exit of any fluid from the tub. A downwardly projecting fin 21 is provided on 19 so that the water will drip into a receptacle without splashing on the floor. 100

110

This part 21 is so arranged that it will not interfere with the normal reciprocation of the tub in the washing machine.

While we have shown and described certain features as constituting our invention, it will be understood that parts have been shown for purposes of illustration only, and that we do not desire to be limited to such details, as obvious modifications will occur to a person skilled in the art.

Having thus fully described our invention, what we claim as new and desire to secure by Letters Patent, is:—

1. In a valve, a casing, an exit opening, a resilient seat therein, a valve member adapted to engage with said seat, means for actuating said valve member into and out of engagement with said seat, and a drain lip on said resilient seat on the exterior of said casing.

2. In a valve, a casing, an exit opening, a resilient seat therein, a valve member adapted to engage with said seat, means for actuating said valve member into and out of engagement with said seat, a drain lip on said resilient seat on the exterior of said casing, and means of introducing liquid into said casing.

3. In combination, a casing an entrance opening in said casing, an exit opening therefrom, an annular resilient member in said exit opening forming a seat therein, said member having a portion to engage the casing and another portion removed therefrom exterior of the casing for draining the liquid away from the casing and the

valve mouth, a valve member adapted to seat in said opening, a Bowden wire control for directing and actuating said valve member, operating means for actuating said Bowden wire above the level of the liquid in said valve, whereby the passage of the liquid out of the casing may be regulated.

4. In a valve seat, an annular portion adapted to engage with a supporting portion, annular walls on either side to embrace the walls of said supporting portion, an aperture through said valve seat, and a semicircular lip connected to said valve seat but spaced therefrom to drain surplus fluids away from said valve seat.

5. In combination, a casing consisting of a chamber, an exit opening and entrance opening, a pear shaped valve member, a bolt and wire centrally located therein, a bolt and wire casing, and means to actuate said wire and said valve member, a resilient valve seat in the exit opening having one portion thereof adapted to yieldingly engage the walls of the exit opening, and a semicircular portion removed therefrom on the exterior thereof but connected therewith, located on the lower half thereof, adapted to drain away fluids and passing therethrough in such a way as to not allow the fluids to run back into the valve or to run along the exterior of the casing.

In testimony whereof, we affix our signatures.

JOSEPH S. POWER.
JOHN W. PEARSON.
